METAL ENVELOPE TUBE AND METHOD OF
SEALING AND EXHAUSTMortimer E. Weiss, Flushing, N. Y., assignor to
Sylvania Electric Products Inc., a corporation
of Massachusetts

Application May 20, 1949, Serial No. 94,380

5 Claims. (Cl. 313—261)

1

The present invention relates generally to the construction of hermetically sealed and evacuated containers and more particularly to envelopes for electron devices and the exhaust and sealing of such envelopes.

An object of the present invention is the provision of a new method for sealing and exhausting a metal envelope electron device and especially sub-miniature electron discharge tubes.

Another object of the present invention is the provision of an improved form of metal envelope sub-miniature tube.

Still another object of the present invention is the elimination of separate sealing and tipping processes now necessary in the construction of hermetically sealed envelopes for electrical circuit elements.

A further object of the present invention is to provide a form of tube structure which will resist the stresses of extreme acceleration supplied to the tube.

Still a further object of the present invention is the simplification of electron discharge tube construction.

The foregoing objects and others which may appear from the following detailed description are accomplished, in accordance with one aspect of the present invention, by providing an envelope which may be evacuated and sealed and which comprises two main parts. One part, the header, comprises a metal eyelet having a flange at one end and a button of glass sealed in the tubular part of the eyelet. The lead-in wires for connection to the elements within the tube pass through and are sealed into the glass button and the operative structure within the tube is supported primarily by extensions of the lead-in wires within the interior of the tube. The second main part of the tube envelope is a tubular metal can closed at one end and having a flange at the other. The metal closure or can may be an active element of the tube such as the anode in a pentode structure or it may, if desired constitute at least in part, a support for a close-spaced anode of a triode structure. The envelope is assembled by replacing the flanged metal can over the header eyelet with the flanges in contact. They are then spot welded together to hold them together as a single unit. The unit is then inserted in a small bell jar connected to an exhaust port of an exhaust machine which may be of conventional form. The bell jar and the tube unit within are then exhausted according to a schedule applicable to such machines. The tube envelope may be heated by induction in several stages of the exhaust schedule. In the final exhaust, a heating coil may be placed over the bell jar whereby a very concentrated radio frequency field is coupled to the adjacent flanges of the envelope causing them to flash weld. Thereafter the evacuated tube may be removed from the bell jar and a conductive get-

2

ter ribbon between one of the external leads and the enclosing envelope flashed electrically to complete the activation of the tube.

The present invention will be more fully understood by reference to the following detailed description, which is accompanied by a drawing, in which Figure 1 illustrates in exploded elevational view an embodiment of the present invention, while Figure 2 illustrates in partial section a bell jar exhaust arrangement for use with the tube structure of Figure 1.

The exploded elevational view shown in Figure 1 includes a metal can 10 hermetically closed at one end by a header 12 and having an outwardly extending flange 14 at the other end. The envelope is completed by a base header 15 including a metallic eyelet having a tubular portion 16 and an outwardly extending flange 18. Sealed within the tubular portion 16 of the eyelet is a glass button 20 through which lead-in conductors 24 pass. To the upper end of lead-in conductors 24 are attached the several internal elements of the tube. In the specific example illustrated in Figure 1, there is included a filamentary cathode 26 attached at its lower end to one of the lead-in conductors 24 and at its upper end to a tensioning arrangement 28. The tensioning arrangement 28 is supported on a rod 30 passing through spacers 32 and 39. At its lower end, rod 30 is connected to another one of the lead-in conductors 24. A number of grids 36 and 38 are concentrically arranged about the cathode 26 and are maintained in position by side rods 40 passing through spacers 32 and 39. Appropriate ones of the side rods 40 are also connected to lead-in conductors 24. In the present embodiment the anode of the tube is constituted by the envelope 10 surrounding the outer grid 38. However, it will be understood that, if desired, a separate anode structure may be provided between the outer grid 38 and the casing 10, and it will be further understood that any desired number of grids may be used. For example a single grid between the cathode and anode structure may be used in the case of a triode tube. Since the evacuated space within the metal envelope is entirely shielded from the influence of exterior fields, it is contemplated that the evacuated envelope be gettered by the use of a conductive ribbon getter 46 connected between flange 18 and one of the lead-in conductors 24.

The electron discharge device according to the present invention is preferably assembled by telescoping the two sections shown in Figure 1 together and spot-welding flanges 14 and 18 together in one or more points in order to maintain their relative position. The unit as thus assembled is inserted as shown in Figure 2 on an exhaust port 50 of an exhaust machine. Port 50 is a conductive tube which may if desired be slit for a distance along its length as indicated at 51.

in order to insure that it is not excessively heated by the radio frequency field used for bombarding and sealing the tube. The port 50 is conductively connected to the frame structure of the exhaust machine. One of leads 24 which is connected to filament 26 is bent outwardly toward one side far enough so that it contacts the exhaust port 50. The others are grouped together so that they contact a central inner tube 52 which is insulated from the remainder of the structure by heavy rubber tubing 53. By making a connection of a source of power to the frame of the exhaust machine and to the inner tube 52, lighting power for the filament 26 as may be required during the exhaust stages is provided. The discharge tube as a whole is covered with a glass bell jar 55 which fits within a compressible rubber sealing sleeve 56. Sleeve 56 is compressed about the lower end of bell jar 55 by a compression ring 57 threaded over a mount member 58. Vacuum is applied to the tube through exhaust tube 52 as indicated by the arrow at the lower end of Figure 2. As the exhaust proceeds, the tube unit may be heated by an external bombarding coil such as coil 60 as required. In the final exhaust stage, a very concentrated radio frequency field of, say 500 kilocycles, is applied by means of another coil 60 closely coupled to the flanges 14 and 18. This makes a radio-frequency flash weld in a small number of cycles of alternation of the 60 cycle supply voltage for the radio frequency generator, say from 2 to 5 cycles. Thus the interior of the tube envelope is hermetically sealed in from $\frac{1}{2}$ to $\frac{1}{40}$ of a second. Thereafter, the compression ring 57 is loosened, relieving the pressure of the rubber sleeve 56 against the lower end of bell jar 55. Bell jar 55 is removed and the completely exhausted electron discharge tube is removed from the exhaust machine. A suitable source of potential is applied between the metal envelope 10 and the one of lead-in conductors 24 which is connected to the internal ribbon getter 46 thus flashing the getter.

It will thus be seen that I have provided an improved type of metal envelope tube which may be made of any convenient size including the extremely small sub-miniature sizes and which does not require separate sealing and tipping processes normally necessary with glass envelopes. The construction has been simplified since the metal envelope may constitute an active element of the tube or it may be used in a conventional manner to support a close-spaced anode for a triode structure. The elimination of a separate anode structure and the sleeves necessary to anchor the supporting micas to the anode leads facilitates assembly. It should be noted that the flanges provided on the stem portion and on the can portion serve a double purpose. They provide the necessary stress relief for the glass base-header from the thermal shock which would occur in welding if the flange were not provided. Because of the comparatively large diameter of flanges 17 and 18, the radio frequency flux used in welding is confined to the outer periphery so that the weld which occurs is restricted to a very narrow zone around the extreme outer edge of flanges 14 and 18. While I have particularly shown and described an embodiment of the present invention, it should be distinctly understood that my invention is not limited thereto, but that modifications within the scope of the invention may be made.

What I claim is:

1. An electron device containing circuit elements within a sealed casing, said casing including a flanged metal body part and a header part, said header part including a flanged tubular metal eyelet having a button of insulating material within the tubular part and a number of lead-in conductors passing through said button, said flanges being welded together around their outer peripheral edges.
2. An electron device containing circuit elements within a sealed casing, said casing including a flanged metal body part and a header part, said header part including a flanged tubular metal eyelet having a glass header button within the tubular part and with a plurality of lead-in conductors passing through said button, said flanges being hermetically joined together in a narrow zone about their outer peripheral edges.
3. An electron discharge device including a casing having two parts, one being a flanged metal can and the other a header part including a flanged tubular eyelet having a glass header button within the tubular part, lead-in conductors passing through said button at least a cathode and a number of control electrodes surrounding said cathode mounted within said casing and connected to said conductors, a number of insulating washers secured to said control electrodes and having their edges bearing against the interior of said can and said flanges being hermetically sealed together around their periphery, said can serving as an anode for said device.
4. The method of fabricating a sealed electron device which in completed form includes a flanged hollow metal body part and a header part including a flanged tubular eyelet and lead-in conductors passing through insulating material in the tubular portion of said eyelet which includes the steps of placing said two parts together with the flanges contacting one another, spot welding said flanges together at a number of points to form a unit, placing said unit in an evacuated container to evacuate the space within said device, heating the outer periphery of said flanges with a high frequency field to cause a complete peripheral weld and thereafter removing said unit from within said container.
5. The method of fabricating a sealed electron device which in completed form includes a flanged metal body part and a header part including a flanged tubular eyelet and lead-in conductors passing through insulating material in the tubular portion of said eyelet which includes the steps of placing said two parts together with the flanges contacting one another, placing said device in an evacuated container to evacuate the space within said device, heating the outer periphery of said flanges with a high frequency field to cause a complete peripheral weld and thereafter removing said device from within said container.
